UNITED STATES PATENT OFFICE.

LAURA M. CASEY, OF CEDAR FALLS, IOWA.

DEVICE FOR PRODUCING PERMANENT WAVES IN HAIR.

Application filed March 19, 1928. Serial No. 262,870.

My invention relates to devices for producing permanent waves in hair, and the object of my improvement is to supply means which coact in such a manner as to produce 5 shaped waves in hair with oppositely directed wave forms and which are crimped in a way transversely as to impart to a tress as a whole permanence in such varied wave forms.

- 10 This object I have accomplished by the means which are hereinafter described and claimed, and which are illustrated in the accompanying drawings, in which Figs. 1 and 2 are like top plans of my assembled 15 device, the movable parts of the device being shown in Fig. 2 as relatively shifted transversely as in treating a tress of hair in shaping it into a permanent wave. Fig. 3 is a longitudinal medial section of said device. 20 Fig. 4 is an elevation of one of the dentated cross-bars of the device taken on a cross section of the inclosing frame. Fig. 5 is a bottom plan of one of the arcuate pressure members or combs of the device. Fig. 6 is 25 an elevation of one of said combs.

My invention is not restricted to the precise construction and arrangement of parts herein shown and described, nor to the various details thereof, as the same may be 30 modified or rearranged in various particulars without departing from the spirit and scope of my invention, one practical embodiment of which has been herein illustrated and described without attempting to show 35 all of the various forms and modifications in which my invention might be embodied.

Different devices have been furnished for the purpose of forming permanent waves in hair, but have been confined to effecting the 40 waves in one plane substantially parallel with the scalp, or if such devices are of that class which require the coiling of a tress around a supporting member helically, the ensuing released and shaped tress has as a 45 result an elongated helical form which is not a true wave and is impermanent.

My improved device is therefore supplied to function in producing a combination wave form in a tress and further to impress upon

each individual hair of the tress transversely 50 in a line across the waved tress an angular crimp which retains its angular bend permanently and thus reinforces and maintains the intermediate waves of the tress.

My device includes a hollow frame having 55 side bars 1 united above and below by like arcuate bars 2 and 3 having respectively outwardly facing convex and concave faces. A plurality of like arcuate and parallel bars 4 are positioned in equally spaced relation 60 across and between the side bars 1 of the frame and united rigidly thereto at their ends. These inner bars 4 have numerous comb teeth 4' along their upper edges, and these may be triangular as shown or otherwise shaped and arranged along the bars as 65 desired.

The numeral 9 denotes a plurality of arcuate comb bodies made of any suitable shape or material, metal or otherwise, and as shown 70 in Figs. 3, 5 and 6, may have longitudinally dentated arcuate comb bars 11, 10 and 12 embedded therein on a lower face thereof arcuate in cross section to have their teeth project therefrom only, and preferably the 75 middle bars 10 have longer teeth than the parallel side bars 11 and 12, the middle teeth on the bars 10 being approximately of the same shape and length as those on the other arcuate frame bars 4.

The curve of each comb bar 9 is taken preferably parallel to the curves of the abutting frame bars 4, and the width of each comb bar 9 is less than the interspace of the bars 4 between which it may be loosely mounted, 85 and also the length of each comb bar 9 is less than the distance between the frame side bars 1 transversely, to permit relative transverse displacements of the comb bars when placed in the frame and manipulated 90 upon a tress according to the principles of this invention.

Apertured projections 5 on the side bars 1 of the frame have their apertures in transverse alignment to removably seat the securing rods 6 which latter may bear against a pair transversely spaced removable bars 7 having handles 8, the bars 7 bearing upon the 95

upper faces of the comb bars 9 when the latter are mounted between the dentated frame bars 4.

In order to treat a tress of hair by means 5 of my appliance, the hair should initially be damped or soaked in water suitably impregnated with an alkali of an appropriate kind, then the tress may be combed out longitudinally carefully to place its hairs in 10 parallel relation, the tress then being overlaid upon the frame bars 4 medially and longitudinally. The concave frame bar 3 is shaped to substantially curve about any region of the scalp when any tress of hair 15 is to be so treated and positioned upon the appliance. Beginning with the nearest interspace of the appliance next the scalp, a comb bar 9 is placed in the interspace medially with its three rows of teeth 10, 11 and 20 12 penetrating the tress downwardly and thus the tress is carried around the bottom of the comb bar as also across both of its longitudinal curvate faces toward and across the dentate frame bar 4. The inserted comb 25 bar 9 is then shifted transversely of said frame a suitable distance as shown in Fig. 2. In this figure the line *a* denotes one hair of such a tress for the sake of clearness, and the first dotted part of the line indicates the 30 curvilinear wave produced in this hair *a* as also in every hair of the tress by the transverse pull thereupon of the penetrating teeth 10, 11 and 12 of the comb bar 9. It will be seen that the hair *a* is thereby placed 35 under longitudinal strain and that where it crosses between teeth 4' of the next opposed frame bar 4, it is bent at about a right angle and this bend is confirmed and rendered permanent by the further pull exerted upon the 40 hair *a* when the next comb bar 9 is inserted and pushed down into and shifted longitudinally reversely in the next succeeding interspace of the frame bars. The same operation is continued until enough comb 45 bars are inserted in the frame to similarly treat each part of the tress, and then the longitudinal bars 7 are placed upon the frame to bear against the tops of the applied comb bars, the cross rods 6 being finally mounted in the apertured ears 5 to releasably lock the bars 7 in place.

While the appliance may be left in place upon the tress until the tress is dry, preferably to save time any suitable heating 55 means may be placed in juxtaposition thereto to dry the tress more quickly.

It will be observed, that when the tress is dried, the same being under strain, the hairs thereof are shaped with a complex 60 wave which sinuously changes direction so that as will be seen at *a* in Fig. 2, and considering the direction of the tress as compressed around the bottoms and sides of the combs 9, waves in different angular directions are produced in the tress between 65

angular bends produced in the hair transversely across the tress due to the carrying of the hairs between teeth 4' of the bars 4 under strain while the hair is damp and drying, steamed or cooked.

These transverse and relatively abrupt crimps as formed in and across the tress at intervals are particularly noticeable when the tress is removed from the appliance and combed out, but it has been proven that the 70 bends persist and thus tend to maintain the reversely alternated waves in the hair permanently.

The hair when so shaped with waves produced therein in opposed directions presents 80 a more natural wavy appearance and pleasing aspect than if waved in one layer substantially parallel to the scalp. The upstanding waves so alternated with the other waves give a relief to the arrangement which is 85 lighter and better ventilated and adds to the apparent mass of the hair.

Having described my invention, what I claim as new, and desire to secure by Letters Patent, is:

1. In combination, an open frame having a plurality of like arcuate fixed and dentated comb bars spaced apart, like arcuate comb bars shorter and wider than the fixed comb bars and having downwardly arcuate faces 90 and narrower than the interspaces thereof mounted loosely therebetween, and means for releasably securing the loose comb bars between the fixed comb bars against removal therefrom in one direction, the comb bars 100 all having rows of longitudinal teeth with those on the wider movable bars directed oppositely to those on the fixed bars.

2. In combination, an assemblage of alternated and approximately parallel arcuate 105 comb devices having respectively oppositely directed teeth, one set being movable alongside the other alternated set longitudinally, the other set having single rows of teeth in their combs, the alternated set having in 110 each comb device a body having along its face opposite the tooth bearing face of the other set parallel rows of teeth, of which one row of teeth is longer than the teeth of the outer rows, and the former bodies having 115 their tooth bearing faces of convex cross section.

3. In combination, an open rigid frame having rigid arcuate parallel cross bars with many teeth along the like edges thereof, and shorter arcuate blocks slidably mounted between said bars, having transversely arcuate faces opposite the toothed edges of the bars and said faces having parallel longitudinal rows of many teeth.

4. In combination, a substantially rectangular open frame having on opposite side bars of one face oppositely alined apertured bearing lugs, longitudinally spaced longitudinal rods crossing the top and bottom 120 125 130

frame bars contactingly, rods crossing the longitudinal rods contactingly with their ends removably inserted in said apertured lugs, said side bars being connected by rigid parallel arcuate transverse bars having on each a single longitudinal row of teeth projecting in the direction toward said securing longitudinal rods, and arcuate bodies shorter than the toothed arcuate bars, slidable therebetween, having transversely arcuate faces directed oppositely from the teeth of said arcuate bars, and having many small teeth arranged along their arcuate faces.

In testimony whereof I affix my signature.

LAURA M. CASEY.
